ATTORNEY

UNITED STATES PATENT OFFICE.

JOHN F. O'CONNOR, OF CHICAGO, ILLINOIS, ASSIGNOR TO WILLIAM H. MINER, OF CHAZY, NEW YORK.

DETACHABLE TWO-PART YOKE.

1,286,734.

Specification of Letters Patent. Patented Dec. 3, 1918.

Application filed August 21, 1916. Serial No. 115,994.

To all whom it may concern:

Be it known that I, JOHN F. O'CONNOR, a citizen of the United States, residing at Chicago, in the county of Cook and State of Illinois, have invented a certain new and useful Improvement in Detachable Two-Part Yokes, of which the following is a full, clear, concise, and exact description, reference being had to the accompanying drawings, forming a part of this specification.

This invention relates to improvements in detachable two-part yokes.

An object of the invention is to provide a two-part cast yoke which may be readily attached to and detached from a standard draw bar or coupler, whether or not the latter has a coupler key slot.

In the drawing forming a part of this specification, Figure 1 is a side elevation of a portion of a draw bar and yoke showing my improvements in connection therewith. Fig. 2 is a horizontal sectional view taken substantially on the line 2--2 of Fig. 1. Fig. 3 is a front elevation of the yoke proper. And Fig. 4 is a perspective view of the connecting block, more particularly hereinafter described.

In said drawing, 10 denotes a coupler having a standard butt provided with the usual upper and lower shoulders 11 and 12. The yoke A comprises two counter-part members B, B, each of which has an upper arm 13, lower arm 14, rear connecting portion 15 and side plate 16 at the front, connecting the ends of the arms 13 and 14. The members B, B are provided at their forward ends at the top, with a detachable inter-locking hinge connection formed by the hinge lugs 17 and 18, the connection being similar to that described in my Patent No. 1,192,221 of July 25, 1916, and which I do not deem it necessary to describe in detail herein. Each of the yoke members B, B is furthermore provided with a shoulder 19, which shoulders are brought into alinement when the yoke members are operatively interlocked and engage with the shoulder 11 of the draw bar butt. Each side plate 16 on the lower half thereof is provided with a series of laterally extended perforated ears 20--20. Preferably, each series of perforated ears 20 comprises three in number, the same being suitably reinforced by the flange portions 21--21, as clearly appears from

Figs. 1 and 2. To hold the lower parts of the yoke together and also to engage the lower shoulder of the draw bar butt, a connecting block C is provided, shown in detail in Fig. 4. The latter comprises a horizontal section 22, upwardly extended side sections 23--23 and a series of outwardly extended perforated ears 24--24 at each end, each series preferably comprising three in number, to correspond to the number of ears on the yoke parts. The block C is assembled with the yoke, as shown in Figs. 1 and 2 and it will be seen that the block engages the lower shoulder of the draw bar butt and thus prevents the draw bar from pulling out. To retain the block C in position, a pair of pins 25 is employed, each pin passing through the perforations in the sets of ears on the sides of the hood. The pins or bolts 25 are held in position by any suitable means such as the cotters 26 which are passed through the perforations 27 in the lower ears of the block C.

By the arrangement provided, it is apparent that the pins 25 are placed in quintuple shear, thus providing an unusually strong and effective connection between said block and the yoke. At their rear ends, the yoke members B, B are preferably provided with a series of over-lapping, perforated ears 28, 85 through which extends a removable bolt 29 to prevent lateral separation of the yoke parts at the rear.

I claim:

1. A yoke of the character described, comprising two members which, when assembled, form a hood at the forward end thereof with an upper shoulder adapted to engage the upper shoulder of a draw bar butt, and a detachable, transversely extending block 95 at the bottom of the hood adapted to engage the lower shoulder of a draw bar butt, and means for attaching said block to the yoke parts, comprising a series of over-lapping perforated ears on the yoke parts and said 100 block, and removable devices extending through said ears.

2. A yoke of the character described, comprising two counter-part, loop shaped members, said members having cooperating, interlocking hinge forming members at their front ends, said members being provided also with laterally extended perforated ears 105 at their forward ends, and a removable, transversely extending block, the latter being 110

provided at each end thereof with a corresponding series of perforated ears arranged to inter-fit with said ears on the yoke members, and vertically arranged removable pins 5 extending through the sets of perforated ears to thereby unite the block with the yoke members.

3. A yoke of the character described comprising, two members arranged side by side 10 longitudinally, said members having detachable inter-locking hinge joint forming portions at their forward ends at the top there-

of, a transversely extending block at the forward end of said members at the bottom thereof, and detachable means for connecting the opposite ends of said block with the respective members and adapted to prevent lateral separation of said members at the bottom of the yoke. 15

In witness that I claim the foregoing I 20 have hereunto subscribed my name this 19th day of Aug., 1916.

JOHN F. O'CONNOR.
